UNITED STATES PATENT OFFICE

133,127

DESIGN FOR A BADGE OR SIMILAR ARTICLE

Ivan J. Caylor, Steubenville, Ohio, and Irvin W. Charnock, Wellsburg, W. Va.

Application March 5, 1942, Serial No. 106,094

Term of patent 3½ years

To all whom it may concern:

Be it known that we, Ivan J. Caylor and Irvin W. Charnock, citizens of the United States, residing at Steubenville, in the county of Jefferson and State of Ohio, and Wellsburg, in the county of Brooke and State of West Virginia, respectively, have invented a new, original, and ornamental Design for a Badge or Similar Article, of which the following is a specification, reference being had to the accompanying drawing, forming part thereof.

We claim:

The ornamental design for a badge or similar article, as shown.

IVAN J. CAYLOR.
IRVIN W. CHARNOCK.
